UNITED STATES PATENT OFFICE

2,445,083

BUBBLE CAP STRUCTURE FOR
FRACTIONATING TOWERS

Merrill R. Reed, Kansas City, Kans.

Application October 15, 1943, Serial No. 506,346

3 Claims. (Cl. 261—114)

1

This invention relates to the oil cracking art and has particular reference to that portion of fractionating towers known as a bubble cap, of which there are a large number disposed at different levels throughout the height of each tower.

One of the important objects of this invention is the provision of a bubble cap structure for fractionating towers, the nature whereof permits quick replacement with a minimum amount of work and without the necessity of workmen entering the towers and subjecting themselves to the dangers incident to such an operation.

Heretofore it has been the common practice to secure the caps of bubble structure in place through the medium of bolts having nuts threaded thereon. The tendency of the bolt and nut structure is to progressively tighten during the interval of use and when removal of the cap held in place is desired, a tremendous amount of work is required even to the extent of necessitating the service of two persons, one below the transverse tray, upon which the cap is positioned, and one thereabove.

An even further object of this invention, therefore, is to provide bubble cap structure with interlocking means, effective while in the assembled condition, yet quickly manipulatable from a position exteriorly of the tower through the employment of a tool long enough to obviate the necessity of the operator entering the main tower body.

A yet further aim of this invention is to provide novel and unique interlocking flue and cap structure for fractionating towers, the parts whereof being secured together by a removable key capable of effecting secure and positive interengagement of the parts, yet susceptible of quick and easy removal when the occasion arises.

Minor objects of the invention will appear during the course of the following specification, referring to the accompanying drawing, wherein:

Fig. 1 is a top plan view of bubble cap structure for fractionating towers, made in accordance with the present invention.

Fig. 2 is a side elevational view of such structure.

Fig. 3 is a sectional view through the bubble cap structure taken on line III—III of Fig. 2; and

Fig. 4 is a stretch-out perspective view illustrating the component parts of the bubble cap structure in disengaged relation.

The function and required duties of a bubble cap is well-known in the art and to those skilled in the business it is understood that the bubble caps are mounted upon a tray 10, several of which

2

are disposed within the fractionating tower. There are a large number of trays 10 disposed horizontally in spaced relation throughout the height of the tower and each tray has a number of openings 12 formed therethrough.

5 A flue 14 is fitted into each of openings 12 respectively, of tray 10 and to insure a tight joint at the zone of juncture between the edge of tray 10 and the outer periphery of the respective flues 14, the latter is flared as at 16. Flue 14 may have its side walls slightly inclined to establish a frusto-conical shaped body having a relatively small diameter at the end opposite to flared portion 16. Through such formation, the flue is 10 rendered easy to insert and remove from its opening in tray 10.

15 An axial stem 18 perforated as at 20 projects beyond the upper annular edge of each flue 14 and is secured in place by a cross head 22 having 20 oppositely bent ears 24 welded or otherwise secured in place.

The cap 26 is specially contoured to receive 25 a key 28, and has a series of legs 30 resting on the upper surface of tray 10 to provide an opening between the lower edge of cap 26 and the upper face of tray 10.

Cap 26 has a closed top wall 32 grooved as at 34 and perforated at a central point to create an opening 36 through which stem 18 is projected 30 when cap 26 is moved to the operative position over flue 14. Groove 34 extends entirely across cap 26 as clearly shown in the drawing.

Key 28 is provided with serrations 37 along its 35 upper inclined face, while its lower horizontal face remains smooth to slide upon the floor of groove 34. A hooked head 38 at one end of key 28 affords an engaging portion for any tool which the operator desires to employ to disengage the key when cap 26 is to be lifted from its position 40 over flue 14. Tongs may be used to place key 28 and a drive fit insures solidity when the wedge action of the key 28 is exerted upon cap 26. Opening 20 in stem 18 is large enough to insure that its lowermost edge will always be below the upper 45 surface of cap 26 and therefore, the bottom of key 28 will always frictionally encounter the outer upper surface of the cap within groove 34.

From the foregoing, it is clear that when a bubble cap structure is in the condition shown in 50 the drawing, and it is desired to replace any part thereof, key 28 may be jerked from place, whereupon cap 26 is lifted from engagement with stem 18 and flue 14 may be dropped through opening 12 in tray 10. Thus, all parts of the bubble cap structure are quickly removable from place and 55

a new set of parts may be installed. In the event it becomes necessary to enter the fractionating tower, an operator may move about upon the tops of the several caps 26 of any particular tray 10 without encountering dangerous or objectionable upwardly projecting parts, for not only does the upper end of stem 18 remain below the plane of wall 32 of cap 26, but the entire body of key 28 lies within the confines of groove 34 with the hooked head 38 thereof well below the upper plane of said end wall 32.

The several parts forming the bubble cap structure and embodying this invention are rugged, inexpensive to manufacture, and easy to manipulate. The same may be re-used after cleaning and none of the parts are weakened by repeated employment. Bubble cap structures having physical characteristics different from those shown in the drawing and described above, may be made without departing from the spirit of the invention or scope of the appended claims.

Having thus described the invention, what is claimed as new and desired to be secured by Letters Patent is:

1. Bubble cap structure for fractionating towers comprising a flue; a perforated stem projecting axially from one end of the flue; a cap, having an opening in the top thereof overlying the said one end of the flue with the stem extending through the said opening; and a key positioned in the perforation of the stem to hold the cap in place, said key having a hook formed on one end thereof.

2. Bubble cap structure for fractionating towers comprising a flue; a perforated stem 35

projecting axially from one end of the flue; a cap, having an opening in the top thereof overlying the said one end of the flue with the stem extending through the said opening; and a key positioned in the perforation of the stem to hold the cap in place, said key having an inclined, serrated face in engagement with the stem and a hook formed on one end thereof.

3. Bubble cap structure for fractionating towers comprising a flue; a perforated stem having a portion thereof projecting axially from one end of the flue; a cap, having an opening in the top thereof overlying the said one end of the flue with the stem extending through the said opening; and a key positioned in the perforation of the stem to hold the cap in place, said cap having a groove formed transversely thereacross with the opening of the cap disposed at the bottom of said groove, said stem and the said key being below the plane of the upper outer face of the cap.
